UNITED STATES PATENT OFFICE.

FRANK F. BURTON, OF EAST HAVEN, CONNECTICUT, ASSIGNOR TO WINCHESTER REPEATING ARMS CO., OF NEW HAVEN, CONNECTICUT, A CORPORATION.

REAR SIGHT FOR FIREARMS.

1,288,379.

Specification of Letters Patent.

Patented Dec. 17, 1918.

Application filed March 29, 1918. Serial No. 225,406.

To all whom it may concern:

Be it known that I, FRANK F. BURTON, a citizen of the United States, residing at East Haven, in the county of New Haven and State of Connecticut, have invented a new and useful Improvement in Rear Sights for Firearms; and I do hereby declare the following, when taken in connection with the accompanying drawings, and the characters of reference marked thereon, to be a full, clear, and exact description of the same, and which said drawings constitute part of this application, and represent, in—

Figure 1 a view in side elevation of my improved interchangeable leaf rear sight for firearms as applied to a gun-barrel which is broken away, the sight being shown with its interchangeable sight leaf in its elevated position.

Fig. 2 a corresponding view showing the sight leaf in its depressed position.

Fig. 3 a plan view of the sight with its leaf depressed.

Fig. 4 a broken view partly in side elevation and partly in vertical section.

Fig. 5 a view in transverse section on the line 5—5 of Fig. 1.

Fig. 6 a detached view in front elevation of the interchangeable sight leaf.

Fig. 7 an edge view thereof.

Fig. 8 a detached view in side elevation of the wedge-like elevator.

Fig. 9 a plan view thereof.

Fig. 10 a view thereof in front elevation.

Fig. 11 a detached view in side elevation of the yielding sight-base.

Fig. 12 a top or plan view of the same.

My invention relates to an improved interchangeable leaf rear sight for firearms, the object being to produce a simple, convenient and efficient sight adapted to have its sight leaf interchanged with sight leaves of a variety of forms and characteristics without any alteration of the rest of the structure, and without recourse to any tools or special appliances for effecting the change.

With these ends in view, my invention consists in an interchangeable leaf rear sight for firearms, characterized by having an interchangeable pivotal leaf in combination with an elevator which holds it in place.

My invention further consists in an interchangeable leaf rear sight having certain de-

tails of construction as will be hereinafter described and pointed out in the claims.

In carrying out my invention as herein shown, I form two downwardly opening hook-like bearings 6—6 separated by a relatively wide clearance-space 7, at the extreme rear end of a yielding plate-like sight-base 8 the forward end of which is widened and formed upon its under face with a transversely arranged dovetail or undercut rib 9 adapted to enter a corresponding groove 10 in the upper face of a gun-barrel 11. The said hook-like bearings 6—6 receive the projecting ends of a pivot-pin 12 permanently mounted in the two positioning-lugs 13—13, of an interchangeable sight leaf 14, the said lugs being spaced apart to fit snugly into the clearance-space 7 aforesaid, perforated for the reception of the said pivot-pin 12, and separated from each other by a space 15 just wide enough for the reception of an inclined rib 16 which rises from the center of a sliding wedge-like elevator 17 the flat lower face of which bears directly upon the gun-barrel and the rear end of which is formed with a roughened thumb-piece 18. The exposed central portion of the pivot-pin 15 enters one or the other of the several range-notches 19 in the rib 16 according to the position of the elevator which is slid longitudinally under the leaf according as it is desired to raise or lower the leaf. For the reception of the forward portion of the elevator 17, the sight-base 8 is formed with a longitudinal slot 20 the rear end of which intersects the clearance-space 7 aforesaid. The positioning-lugs 13, 13, are formed with faces 21 and 22 located at substantially right angles to each other and co-acting with inclined surfaces 23 on opposite sides of the notched rib 16 for holding the leaf in its erect position as shown in Figs. 1 and 5, or in its depressed position as shown in Figs. 2, 3 and 4. The said leaf is formed in the usual manner with a sighting-notch 24 around which the metal of the leaf is reduced in thickness for the purpose of definition, by a cup-shaped recess 25 which is the ordinary practice. The forward face of the leaf 14 is slightly grooved at opposite points as at 26, for the reception of the projecting ends of the pivot-pin 12.

My improved sight is used for sighting purposes in the ordinary manner by erecting

or depressing its pivotal leaf, according as it is desired to use the sight or not. If it is desired to interchange the leaf with a leaf of a different form or characteristics, the 5 user of the arm has nothing to do but to grasp the leaf and so lift the same vertically and thus sufficiently spring the yielding sight-base to permit the elevator to be withdrawn, after which the leaf is readily re- 10 moved from the base by disengaging its pivot-pin from the downwardly opening hook-like bearings thereof after which another leaf of different form and characteristics, but having a pivot-pin of the same size 15 and length, may be engaged with the base after which the elevator is restored to its place.

All this may be done in a moment's time, and without the use of any tools so that a 20 sight, if provided with a set of interchangeable leaves of a variety of forms and characteristics, may be readily adapted to any kind of shooting, or to the visual powers of the individual.

25 I claim:—

1. An interchangeable leaf rear sight for firearms, having a yielding sight-base formed at its rear end with two open pivot-bearings, a pivotal sight leaf furnished with a rigid 30 pivot-pin the respective projecting ends of which enter the said open bearings in the sight-base, and an adjustable elevator constructed to normally hold the ends of the pins in such open bearings.

35 2. An interchangeable leaf rear sight for firearms, having a yielding sight-base formed at its rear end with two open pivot-bearings, a sight leaf furnished with a rigid pivot-pin the respective projecting ends of which 40 enter the said open bearings in the sight-base, and a wedge-like elevator constructed to en-

gage with the ends of the pin for normally holding them in such open bearings.

3. An interchangeable leaf rear sight for firearms, having a yielding sight-base formed 45 at its rear end with two downwardly opening hook-like bearings, in combination with a sight leaf carrying a pivot-pin adapted to be removably engaged with the said bearings, and means for holding the said pin in 50 the said bearings, when the leaf is in use.

4. An interchangeable leaf rear sight for firearms, having a yielding sight-base formed at its rear end with two open bearings, a sight leaf having a rigid pivot-pin the re- 55 spective projecting ends of which enter the said open bearings in the sight-base, and an adjustable elevator having range-notches which engage with the projecting ends of the pin for normally holding the same in the said 60 open bearings in the sight-base.

5. An interchangeable leaf rear sight for firearms, having a yielding sight-base formed at its rear end with two downwardly opening hook-like bearings separated by a clear- 65 ance-space, a sight leaf formed with two separated positioning-lugs having bearing faces and carrying a pivot-pin adapted to have bearing in the said bearings, and an adjustable elevator formed with inclined surfaces upon which the said lugs ride, and having an upwardly projecting notched rib which enters the space between the said lugs for co-action with the central portion of the 70 said pin.

In testimony whereof, I have signed this specification in the presence of two subscribing witnesses.

FRANK F. BURTON.
